Filed June 17, 1966, Ser. No. 558,290
24 Claims. (Cl. 229—17)

This invention relates to a container. The invention relates more particularly to a portable disposable type of container for liquid materials, or powder materials, or granular materials, or the like.

It is an object of this invention to provide a container which is easily manually grasped for movement thereof or for pouring therefrom.

It is another object of this invention to provide such a container which can be constructed from a single sheet or blank of cardboard, paperboard, or plastic, or the like.

It is another object of this invention to provide a container which has considerable strength to withstand internal or external pressures.

It is another object of this invention to provide such a container, which in quantity can be easily and readily stacked.

Another object of this invention is to provide such a container in which the center of gravity of the material therein shifts to a lesser degree toward the pouring spout than in a conventional container during pouring of the material, thus facilitating the pouring operation.

Another object of this invention is to provide such a container which can be constructed in any one of various shapes and sizes.

Another object of this invention is to provide such a container which can be produced at relatively low costs.

Other objects and advantages reside in the construction of the invention, combinations thereof, the method of manufacture, and the mode of operation, as will become more apparent from the following description.

In the drawings:

FIGURE 1 is a perspective view of a container of this invention.

FIGURE 2 is a perspective view, drawn on a smaller scale, showing a plurality of containers of this invention and illustrating the stacking thereof.

FIGURE 3 is a perspective view drawn on substantially the same scale as FIGURE 1 and showing a container of this invention as the container is manually grasped and as material is poured therefrom.

FIGURE 4 is a sectional view taken substantially on line 4—4 of FIGURE 1.

FIGURE 5 is a plan view of one side surface of a sheet or blank or material formed for construction of the container of FIGURE 1.

FIGURE 6 is a plan view of the opposite side surface of the sheet or blank of material of FIGURE 5.

FIGURE 7 is a perspective view, drawn on a reduced scale, of the sheet or blank of FIGURES 5 and 6 as it is formed for storage or for shipment or the like after completion of the first step in formation of a container therefrom.

FIGURE 8 is a perspective view of the sheet or blank of FIGURES 5, 6, and 7, illustrating additional steps in formation of a container therefrom.

FIGURE 9 is a fragmentary perspective view, illustrating the steps in formation of the bottom part of a container from the sheet or blank of material shown in FIGURES 5, 6, 7, and 8.

FIGURE 10 is a fragmentary perspective view illustrating the final step in formation of the upper part of a container from the sheet or blank of material shown in FIGURES 5, 6, 7, 8, and 9.

FIGURE 11 is a fragmentary perspective view illustrating the final step in formation of the bottom part of a

2

container from the sheet or blank of material shown in FIGURES 5, 6, 7, 8, 9, and 10.

FIGURE 12 is a perspective view of the container of FIGURES 1-11, with opposed side panels curved outwardly, rather than inwardly.

FIGURE 13 is a sectional view taken substantially on line 13—13 of FIGURE 12.

FIGURE 14 is a plan view of a sheet or blank of material formed for construction of another container of this invention.

FIGURE 15 is a perspective view of a container formed from the blank shown in FIGURE 14.

FIGURE 16 is a perspective view of another container of this invention.

FIGURE 17 is a sectional view taken substantially on line 17—17 of FIGURE 16.

FIGURE 18 is a plan view drawn on a reduced scale of a blank or sheet used for forming the container of FIGURES 16 and 17.

FIGURE 19 is a perspective view of another container of this invention.

Referring to the drawings in detail, a container 16 constructed according to this invention is shown in FIGURE 1. The container 16 is made from a generally coplanar sheet or blank 18 shown in FIGURES 5 and 6. The sheet or blank 18 is formed in a predetermined irregular configuration as illustrated. The sheet or blank 18 is made of any suitable material, preferably, cardboard or paperboard or plastic or the like.

30 The sheet or blank 18 has a rectangular side panel 20 and a rectangular side panel 22. Intermediate the rectangular side panels 20 and 22 is a side panel 24 which has edges 25 which converge. Thus, the side panel 24

35 may be referred to as trapezoidal in shape. A side panel 26 has converging edges 27 and is also trapezoidal in shape. The rectangular side panel 22 is intermediate the trapezoidal side panels 24 and 26. Thus, one side edge 27 of the rectangular side panel 22 coincides with a side edge 27 of the trapezoidal side panel 26, and the other side

40 edge 25 of the rectangular side panel 22 coincides with a side edge 25 of the trapezoidal side panel 24. The trapezoidal side panel 26 has an upper edge 21 and a lower edge 23, which are substantially parallel one with respect to the other. The trapezoidal side panel 24 has an upper edge 28 and a lower edge 29 which are substantially parallel one with the other. The trapezoidal side panels 24 and 26 are shown as having the same dimensions, but are inverted one with respect to the other.

The rectangular side panel 20 has lower and upper edges 33 which are equal in length and parallel one with

45 the other. The rectangular side panel 22 has lower and upper edges 35 which are equal in length and parallel one with the other.

The rectangular side panel 20 has a flap 30 at one end

50 thereof and a flap 32 at the other end thereof. The rectangular side panel 22 has a flap 34 at one end thereof and a flap 36 at the other end thereof.

The trapezoidal side panel 24 has a flap 38 at one end

55 thereof and a flap 40 at the other end thereof. A fold line 42 is shown bisecting the trapezoidal panel 24 and the flaps 38 and 40. The trapezoidal side panel 26 has a flap

60 44 at one end thereof and a flap 46 at the other end thereof. A fold line 48 is shown bisecting the trapezoidal side panel 26 and the flaps 44 and 46.

A flap 50 joins the flap 30, and a flap 52 is joined to the

65 flap 50 and to the flap 38. A flap 54 is joined to the flap 38 and to a flap 56. The flap 56 is also joined to the flap 36. A flap 58 is disposed intermediate the flap 36 and the flap 46. A flap 60 is also joined to the flap 46.

An attachment strip 62 is joined to the flap 60. An

attachment strip 64 extends from one end of the attachment strip 62. The attachment strip 64 is disposed along

the edge of the trapezoidal side panel 26. An attachment strip 66 extends from the other end of the attachment strip 64 and is joined to a flap 68 which is also joined to the flap 44.

A flap 70 is disposed intermediate the flap 44 and the flap 34 and is joined thereto. A flap 72 is disposed intermediate the flap 34 and the flap 40 and is joined thereto. A flap 74 is disposed intermediate the flap 40 and the flap 32 and is joined thereto.

Preferably, suitable fold lines are formed in the blank 18 by scoring or the like along the edges of the side panels and between adjacent flaps and strips.

Any suitable adhesive material may be employed to secure portions of the blank 18 one to the other to form a container 16. Preferably, pressure-sensitive or temperature-sensitive adhesive material is applied to the strips 62, 64, and 66 and to flaps 60, 58, 68, 70, 72, and 74 of the surface of the blank 18 as illustrated in FIGURE 5. Such adhesive material is also applied to the surface of the flaps 58, 60, 72, 74, 70, and 68 of the blank 18 as shown in FIGURE 6. Adhesive material is also applied, as shown in FIGURE 6, to a strip 80 at the edge of the flap 30 and to a strip 81 at the edge of the flap 50 and to a strip 82 at the edge of the flap 52 and to a strip 83 at the edge of the flap 54 and to a strip 85 at the edge of the flap 34. It is to be understood, of course, that adhesive material other than pressure-sensitive or temperature-sensitive adhesive material or other attachment means may be employed in regard to a container of this invention.

If desired, the blank 18 may be folded upon the fold lines 42 and 48. The surfaces of the strips 62, 64, and 66 to which adhesive material has been applied, as shown in FIGURE 5, are then placed into engagement with the right hand edge of the flaps 30 and 32 and the panel 20 for attachment thereto. Thus, the strips 62, 66, and 64 are secured to the edge of the flaps 30 and 32 and the panel 20, respectively. The blank 18 then appears substantially as shown in FIGURE 7. If pressure-sensitive adhesive material is employed, protective sheet material (not shown) is used to cover the other portions of the blank 18 to which the pressure-sensitive material has been applied to prevent adhesion with any other surface or element. In the form shown in FIGURE 7 the blank 18 can be easily stored for future use. Also, in the form shown in FIGURE 7, the blank 18 can be readily packed for shipping.

It is to be understood that the blank 18 does not need to be first formed into the shape shown in FIGURE 7 in order to form a container. If the step shown in FIGURE 7 is eliminated, the fold lines 42 and 48 do not appear in the blank 18 as it is shown in FIGURES 5 and 6.

The next step in forming the blank 18 into a container 16 is that of opening the blank 18 to substantially the form thereof shown in FIGURE 8. Any protective sheet material employed to cover the adhesive material is removed therefrom.

As shown in FIGURE 9, the bottom of the container 16 is formed by folding the flaps 68 and 70 to cover the flap 44 as the flaps 68 and 70 are adhesively attached to the flap 44 by applying pressure thereto. The opposite surface of the flap 70 is adhesively attached to the flap 34 as the flap 34 is folded over the flap 70. The flaps 72 and 74 are folded into engagement with the flap 40 for adhesive attachment of one surface of each of the flaps 72 and 74 to the flap 40. The opposite surface of the flap 72 is attached to the flap 34. The flap 74 has the opposite surface thereof attached to the flap 32. Then, the strip 85 of the flap 34 is moved into position to cover a part of the flap 32 as the strip 85 is adhesively attached thereto.

As shown in FIGURE 10, the top part of the container 16 is formed by folding the flaps 58 and 60 into engagement with the flap 46 so that one surface of each of the flaps 58 and 60 is attached to the flap 46. The opposite surface of the flap 58 is attached to the flap 36 as the flap

36 folds over the flap 58. The opposite surface of the flap 60 is attached to the flap 30 as the flap 30 folds over the flap 60. Then, the flaps 52 and 54 are folded to cover the flap 38. The adhesive strip 82 upon the flap 52 shown in FIGURE 6 is attached to the flap 50, and the adhesive strip 83 upon the flap 54 shown in FIGURE 6 is attached to the flap 56. Following this, the strip 80 of the flap 30 and the strip 81 of the flap 50 are moved into position to cover a part of the flap 36 and to cover a part of the flap 56, as illustrated in FIGURE 10, as the strips 80 and 81 are adhesively attached thereto.

Thus, the container of FIGURE 1 is formed. It is to be noted that as the container 16 is formed, the upper edges 21, 35, 28, and 33 of the side panels 26, 22, 24, and 20, respectively, become substantially coplanar and the bottom edges 23, 35, 29, and 33 of the side panels 26, 22, 24, and 20, respectively, become substantially coplanar. Thus, the bottom and top surfaces of the container 16 formed by the various flaps are substantially flat and parallel. Thus, the container 16 has a substantially flat cover at the top thereof and a substantially flat base at the bottom thereof.

Either the bottom part of the container 16 or the top part thereof may be formed first. The container 16 may be filled through either the top or the bottom thereof when that part of the container 16 is disposed upwardly.

The container 16 is adapted to contain a liquid or a powder material, or a granular material, or the like.

As illustrated in FIGURE 3, the flaps 52, 54, 38, 50, 30 and 56 are adapted to form a pouring spout. The pouring spout is formed as follows: The flaps 52 and 54 are lifted away from the flap 38, thus separating the strip 81 from adhesive attachment with the flap 56. Then, the flaps 52 and 54 are separated from adhesive attachment with the flaps 50 and 56, respectively. Then, the flap 38 is pulled forwardly and formation of the pouring spout is completed. In order to permit such formation of the spout after assembly of the container 16, adhesive attachment of the flaps 52 and 54 to the flap 38 is to a rather limited degree.

It is to be noted that in the formation of the container 16 shown in FIGURE 1, the panels 20, 24, 22, and 26 shown in FIGURES 5 and 6 form the side walls of the container 16. The surfaces of the side panels 20, 24, 22, and 26 shown in FIGURE 5 become the exterior surfaces thereof. As shown and discussed, the panels 20 and 22 are rectangular in shape. Thus, the upper edge 35 of the panel 22 is equal in length to the bottom edge 35 thereof and the upper edge 33 of the side panel 20 is equal in length to the bottom edge 33 thereof. The panels 24 and 26 have side edges 25 and 27, respectively, which converge. The side edges 25 of the panel 24 converge toward the upper part of the container 16 and the side edges 27 of the panel 26 converge toward the bottom part 55 of the container 16. Thus, the upper edge 21 of the side panel 26 is longer in length than the bottom edge 23 thereof and the upper edge 28 of the panel 24 is shorter in length than the lower edge 29 thereof.

Also, as stated above, the bottom and top surfaces 60 of the container 16 are substantially flat and parallel. Therefore, when the blank 18 is formed into the container 16, there is relative lateral angular movement between the upper edge 35 of the side panel 22 and the bottom edge 35 thereof, so that the upper edge 35 and the bottom edge 35 of the panel 22 become disposed in different planes. Also, in like manner, the upper edge 33 of the side panel 20 and the bottom edge 33 thereof become disposed in different planes. Thus, the rectangular panels 20 and 22 each assume a curved shape. FIGURES 1, 3, 4 and 8 show the rectangular side panels 20 and 22 curved inwardly. FIGURES 12 and 13 show the rectangular side panels 20 and 22 curved outwardly. Because of the outward curvature of the side panels 20 and 22, rather than an inward curvature thereof, the volumetric capacity of the container 16 of FIGURE 12 may be some-

what greater than the volumetric capacity of the container 16 of FIGURE 1.

Such curvature of the panels or side walls 20 and 22 provides strength to the container 16 which would not otherwise be possible. The container 16 is capable of resisting appreciable internal or external pressures or forces without distortion or collapse thereof.

Due to the fact that the upper and lower surfaces of the container 16 are substantially flat and parallel, and due to the fact that a container 16 is capable of resisting appreciable external forces, a plurality of containers 16 can be stacked one upon another, as illustrated in FIGURE 2. Even though a plurality of containers 16 are filled with material, the containers 16 can be stacked in a plurality of layers.

Furthermore, the concave side panels 20 and 22 of the container 16 of FIGURE 1 provide recesses which facilitate manual grasping of a container 16 during pouring therefrom, as illustrated in FIGURE 3, or for any handling of the container 16. When the container 16 is disposed at an angle for pouring therefrom, as illustrated in FIGURE 3, the center of gravity of the container 16, including the contents thereof, shifts to a lesser degree toward the pouring spout than occurs in pouring from a conventional type of container which is substantially a parallelepiped. This is due to the fact that most of the material within the container 16 rests upon the trapezoidal side panel 24 of the container 16 which is lowermost during pouring therefrom as illustrated in FIGURE 3. The trapezoidal side panel 24 has a smaller portion adjacent the pouring spout than the portion thereof spaced from the pouring spout. Therefore, while material is being poured from the container 16, the material moves into a part of the container 16 adjacent the pouring spout which is smaller in volume than a part of the container 16 which is farther from the pouring spout. Thus, the center of gravity of the container 16 and the material therein does not shift greatly toward the pouring spout during pouring of the material. Therefore, the container 16 is readily handled and controlled during pouring therefrom.

It is to be understood that a container of this invention can be produced in any one of various shapes and configurations. The shape of the container of this invention depends upon the relative dimensions of the opposed side panels, such as the panels 20 and 22, and the relative dimensions of the opposed side panels, such as the panels 24 and 26, in which the edges converge or diverge. The shape of a container of this invention also depends upon the shape of the side edges of the side panels of the container.

FIGURE 14 shows a blank 106 for construction of another container of this invention. The blank 106 has opposed side panels 108 and 109, which are similar in shape. The side panel 108 has side edges 110 which generally converge upwardly so that an upper edge 112 of the side panel 108 is shorter in length than a bottom edge 114 thereof. The side panel 109 has side edges 110 which generally converge downwardly so that an upper edge 114 of the side panel 109 is longer in length than a bottom edge 112 thereof.

The blank 106 also has opposed side panels 118 and 119. Each of the side panels 118 and 119 has curved side edges. The side panel 119 has a side edge 110 which coincides with a side edge 110 of the side panel 109. The side panel 119 also has a side edge 110 which coincides with a side edge 110 of the side panel 108. The side panel 118 has a side edge 110 which coincides with one of the side edges 110 of the side panel 108. The side panel 118 also has a side edge 120. Each of the side panels 118 and 119 has an upper edge 122 which is equal in length to a bottom edge 124 thereof.

The blank 106 is shown as having suitable upper flaps 126 and suitable bottom flaps 128 which serve in a manner similar to that of the flaps of the blank 18 shown in

FIGURES 5 and 6. A strip 129 extends along the side panel 109 for attachment to the side panel 118.

The blank 106 of FIGURE 14 may be formed into a container 130 shown in FIGURE 15. The opposed side panels 118 and 119 of the container 130 curve inwardly while the opposed side panels 108 and 109 curve outwardly, as shown in FIGURE 15. However, one or both of the opposed side panels 118 and 119 may curve outwardly, rather than inwardly.

FIGURES 16 and 17 show a container 140 which is formed from a blank 142 shown in FIGURE 18. The blank 142 has opposed side panels 144, each of which has opposed side edges 146 which curve one toward the other. The blank 142 also has opposed side panels 147, each of which has the mutual side edges 146 of the side panels 144. However, the opposed side edges 146 of the panels 147 curve one away from the other. Each of the side panels 144 has an upper edge 148 which is equal in length to a bottom edge 148. One of the side panels 147 has an upper edge 150 which is shorter in length than its bottom edge 152. The other side panel 147 has an upper edge 152 which is longer in length than its bottom edge 150. The opposed side edges 146 of one of the panels 147 converge upwardly and the opposed side edges of the other side panel 147 converge downwardly.

Suitable flaps 160 are integrally arranged at the top and bottom of the side panels 144 and 147.

FIGURE 19 shows a container 190 of this invention. The container 190 has two opposed rectangular side panels 192 and two opposed side panels 194 which have converging edges 196. The converging edges 196 converge to a point 198. The side panels 192 are shown curved inwardly, but may curve outwardly.

The container 190 has a top cover 200 and a base 202. A pouring spout or aperture 204 is shown in the cover 200 for use if desired.

It is to be understood that a container of this invention is capable of withstanding relatively high external and/or internal pressures and forces without distortion or collapse. Furthermore, a container of this invention which has side portions which curve inwardly may be easily and readily manually grasped for handling thereof.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

The invention having thus been described, the following is claimed:

1. A container of paperboard material or the like comprising:

a body formed from a single sheet of material, the body having a bottom base and a top base, the bases being substantially parallel one with the other, the body also having a plurality of side portions which extend between the bottom base and the top base, there being a pair of opposed side portions which have edges which converge, one of said side portions having edges which converge from the top base to the bottom base and the other of said side portions having edges which converge from the bottom base to the top base, there also being a pair of opposed side portions of the body each of which has a curved surface.

2. The container of claim 1 in which the last said pair of the side portions is rectangular in shape.

3. The container of claim 1 in which the side portions which have converging edges are trapezoidal in shape.

4. The container of claim 1 in which the side portions which have converging edges are triangular in shape.

5. The container of claim 1 in which the bottom base

and the top base each comprise a plurality of flaps which are attached together.

6. The container of claim 5 in which some of the flaps which comprise the top base are relatively movable to form a pouring spout.

7. The container of claim 5 in which the flaps are adhesively attached together.

8. The container of claim 1 in which at least one of the side portions has at least one edge which is curved.

9. A container of paperboard or the like comprising: 10 a substantially flat base,

a tubular body extending upwardly from the base, the tubular body having four side walls, each of the side walls having an upper edge which is substantially parallel with the base, the upper edge of each 15 of the side walls being substantially coplanar with the upper edge of each of the other side walls, one of the side walls of the container having side edges which converge from the base to the upper edge thereof, there being a side wall which is opposite 20 said one of the side walls, said side wall which is opposite said one of the side walls having side edges which converge from the upper edge thereof to the base of the container, each of the other two side 25 walls of the container having a curved surface.

10. Structure of the type described comprising:

a sheet of material, the sheet of material having a pair of spaced-apart bases, the sheet of material also having a plurality of side surfaces extending between the bases, one of the side surfaces having side edges which converge to one base from the other base, another side surface having side edges which converge from the said one base to the other base, the side surface which has side edges which converge to one base being spaced from the side surface which has side edges which converge to the other base.

11. The structure of claim 10 in which the bases are parallel one with respect to the other.

12. The structure of claim 10 in which the side surfaces of the body are four in number and in which said side surface which has side edges which converge to one base is opposite from the side surface which has side edges which converge to the other base.

13. The structure of claim 10 in which said side edges are curved.

14. The structure of claim 10 in which said side edges are substantially straight.

15. The structure of claim 11 in which two opposed side surfaces are rectangular in shape and two opposed side surfaces are trapezoidal in shape.

16. The structure of claim 10 in which at least one of the side surfaces is curved.

17. A container comprising:

a sheet of material provided with a substantially coplanar bottom base and a substantially coplanar top cover, the bottom base and the top cover being substantially parallel one with the other, there being a plurality of side panels extending between the bottom base and the top cover, each of the side panels having an upper edge which is substantially coplanar with the top cover, each of the side panels having a lower edge which is substantially coplanar with the bottom base, there being a side panel in which the upper edge thereof is substantially equal in length to the lower edge thereof and in which the upper edge thereof is in a plane different from the plane of the lower edge thereof, there being a side panel in which the upper edge thereof is shorter in length than the lower edge thereof, there being a side panel in which the upper edge thereof is longer in length than the lower edge thereof.

5

18. A blank for producing a container comprising: a one-piece sheet, the sheet having at least four contiguous side panels which are arranged laterally and which are connected on mutual side fold lines, each side panel also having a top fold line and a bottom fold line, the top fold line and the bottom fold line of each side panel being parallel one with respect to the other and spaced apart a given distance so that the spacing between the top fold line and the bottom fold line of each side panel is equal to the spacing between the top fold line and the bottom fold line of each of the other side panels, two of the side panels having a given area and shape and having spaced apart positions on the sheet, two of the side panels having an area and shape which is different from the given area and shape, the last said two side panels being positioned on the sheet with one of the first said side panels therebetween, each of the last said two side panels having a top fold line which is of a length different from the length of the bottom fold line thereof, the last said two side panels being reversed one with respect to the other so that the bottom fold line of one of the last said two side panels is shorter in length than the top fold line thereof while the other of the last said two side panels has a bottom fold line which is longer in length than the top fold line thereof.

19. The blank of claim 18 in which the top fold line of one of the last said two side panels is equal in 30 length to the bottom fold line of the other of the last said two side panels.

20. The blank of claim 19 in which the area of one of the last said two side panels is equal to the area of the other of the last said two side panels.

21. The blank of claim 18 in which two of the side panels are rectangular and two of the side panels are trapezoidal.

22. The blank of claim 18 in which there is a plurality of flaps, there being at least one flap joined to a 40 top fold line and at least one flap joined to a bottom fold line.

23. The blank of claim 22 in which a plurality of flaps is attached to a top fold line of at least one of the panels and in which a portion of the flaps form a pouring spout.

24. A container of paperboard or the like comprising: a bottom base; a tubular body member extending upwardly from the bottom base and attached thereto, the tubular body member having a plurality of side panels, there being a plurality of rectangular side panels, there being a plurality of trapezoidal side panels, there being one trapezoidal side panel intermediate two rectangular side panels, there being one rectangular side panel intermediate two trapezoidal side panels, each of the side panels having a pair of edges extending upwardly from the bottom base, the edges of at least one of the trapezoidal side panels converging toward the bottom base, the edges of at least one of the trapezoidal side panels converging away from the bottom base.
